CLAIM

The ornamental design for a vehicle turn signal light, as shown and described.

DESCRIPTION

FIG. 1 is a left, front perspective view of a vehicle turn signal light showing our new design;

FIG. 2 is a right, rear perspective view thereof;

FIG. 3 is a front perspective view of a second embodiment of our design.

The end, side and rear configuration of both embodiments are identical.

FIG 1

FIG 2

FIG 3
